Design No 462.

Samuel D. Vose - Design for a Parlor Stove

Fig 1

Patented June 22. 1852.

Sam'l D. Vose
Parlor Stove

Sept 1851
Albany N.Y.

UNITED STATES PATENT OFFICE.

SAMUEL D. VOSE, OF ALBANY, NEW YORK.

DESIGN FOR A PARLOR-STOVE.

Specification forming part of Design No. 462, dated June 22, 1852.

To all whom it may concern:

Be it known that I, SAMUEL D. VOSE, of Albany, county of Albany, and State of New York, have invented or produced a new ornamental Design for a Parlor-Stove; and I do hereby declare that the following is a full and exact description of the same, reference being made to the annexed drawing, affixed to and making part of this specification.

The figure 1 represents the parlor-stove, being a perspective view of the entire stove.

U represents the urn. T represents the top. F represents the front. (The back, not seen in the drawing, is a fac-simile of the front.) E represents the end, (the opposite end, not seen in the drawing, being a fac-simile of the same.) B represents the bottom. L represents the legs.

My invention consists in the combination of the several moldings and ornaments as arranged in the whole stove, and is not easily described in words, and reference is therefore made to the drawing.

I do not claim any detailed part of the moldings or configuration.

What I claim as my invention, and desire to secure by Letters Patent, is—

The combination of the several moldings and ornaments as arranged together, the whole forming an ornamental design for a parlor-stove, as herein set forth and described.

SAML. D. VOSE.
